ELEVATOR PLATE MECHANISM

Elisha E. Alexander, Chicago, Ill.

Application January 2, 1935, Serial No. 16

8 Claims. (Cl. 187—1)

This invention relates to elevator plate mechanisms and more particularly to a sill for spanning the space between the floors of a building and elevator structure.

5 It contemplates more especially the provision of a sill plate that constitutes a component part of the elevator cab and is within the control of the operator to also serve as a safety feature while the elevator is in vertical movement. With 10 the use of freight elevators, there is a constant source of danger and accidental damage due to the fact that the space between the floors of an elevator and building structure presents much difficulty in wheeling loaded and empty trucks 15 thereafter. The wheels of the trucks are caught in the unprotected space even though the floors of an elevator and building structure are in horizontal alignment, but there is even a greater hazard when the elevator is slightly above or below 20 the building floor landing which customarily occurs in the ordinary use of a freight elevator.

Then, too, most elevators present the hazard of permitting loaded or unloaded trucks to roll toward the wall of the building structure while the 25 elevator is in motion. This results in serious accidents and gives rise to much damage to the building and elevator structure to the end that freight elevators present serious problems in safety and accident prevention. This coupled 30 with the fact that it requires great care and an extended period of time to load and unload trucks in connection with elevator operation, renders it an important advantage to provide a sill that constitutes an adjunct of the elevator and serves 35 a dual purpose of precluding the accidental removal of loaded trucks as well as affords the speedy displacement thereof to the building floor landing when the elevator is brought to rest at any desired floor even though actual floor alignment is not accomplished, because the sill plate 40 will compensate for slight variations either above or below the building floor landing.

One object of the present invention is to simplify the construction and improve the operation 45 of devices of the character mentioned.

Another object is the provision of a novel elevator plate mechanism that serves the dual purpose of a safety expedient as well as a floor sill to bridge the gap between an elevator and building floor structure.

Still another object is the provision of means in conjunction with an elevator car for precluding the accidental removal of trucks therefrom as 55 well as to serve as a floor sill to afford truck

displacement between elevator and building floor structures.

A further object is to provide an elevator plate mechanism that is mounted to the floor of an elevator so as to be capable of manipulation to serve 5 as a safety feature and as a floor sill.

A still further object is the provision of means for operating a plate mechanism between horizontal and vertical planes in connection with an elevator floor for the purpose set forth. 10

Still a further object is the provision of a floor sill for freight elevators that is power operated and is automatically controlled within predetermined limits of pivotal displacement.

Other objects and advantages will appear from 15 the following description of an illustrative embodiment of the present invention.

In the drawings:

Figure 1 is a sectional view in elevation of a 20 building and elevator structure having a plate mechanism embodying features of the present invention.

Figure 2 is a view similar to Figure 1 showing the plate mechanism in a vertical position to 25 serve as a safety feature in conjunction with elevator operation.

Figure 3 is a sectional view taken substantially 30 along line III—III of Figure 1.

Figure 4 is a sectional view taken substantially 35 along line IV—IV of Figure 2.

Figure 5 is a sectional view corresponding with 40 Figure 1 of a modified embodiment showing the actuating mechanism disposed beneath the elevator floor.

Figure 6 is a conventional wiring diagram of 45 the controls utilized in actuating the plate mechanism disclosed in Figures 1 to 5 inclusive.

Figure 7 is a view similar to Figure 5 of a still 50 further modified embodiment of the present invention, it showing a simpler form of link actuating mechanism.

Figure 8 is a sectional view taken substantially 55 along line VIII—VIII of Figure 7.

Figure 9 is a sectional view similar to Figure 7 showing a still further modified embodiment of 45 the plate actuating mechanism.

Figure 10 is a view similar to Figure 9 of still 50 a further modified embodiment of the plate actuating instrumentalities.

Figure 11 is a view similar to Figure 7 showing 55 a counterbalancing mechanism in conjunction therewith to minimize the power requirements in actuating the plate mechanism.

Figure 12 is a view similar to Figure 11 with a 55 spring mechanism operatively connected there-

with in lieu of the counterweight disclosed in Figure 11 for the purpose set forth.

Figure 13 is a fragmentary view of a hand operated plate actuating instrumentality for use in connection with any of the above described embodiments in lieu of the motor or other power source.

The structure selected for illustration is shown in association with a building wall 10 having a substantially rectangular opening 11 provided therein to define a doorway or opening 12 to an elevator shaft 13 where passage over the building floor 14 is necessary for ingress or egress from an elevator 15. The elevator 15 is slidably mounted for vertical movement within the shaft 13 in the customary manner by instrumentalities of standard construction. To this end, the elevator 15 is provided with a floor 16 that must be in substantial alignment with the superposed building floors 14 constituting landings for the elevator floors 16. Any suitable control 17 of standard construction may be mounted in the wall of the elevator 15 to operate and effect the ascent or descent of the elevator 15 in the customary manner.

The doorway or opening 12 is closed to preclude passage therethrough as well as to decrease the fire hazard to a minimum by a suitable door of any type, in this instance there being shown meeker door sections 18 and 19 that are guided for approach and separation in guides 20 mounted between the floors 14 and 16 of the building and elevator structures 10 and 15, respectively. To this end, there is a space or gap 21 between the building floor landing 14 and the adjacent end of the elevator floor 16 which is preferably covered by an elevator plate mechanism constituting the subject matter of the present invention.

In order to bridge the space or gap 21 between the floors 14 and 16 of the building and elevator structures, an elongated metallic plate 22 of substantially rectangular configuration is mounted so that the linear edge 23 thereof is in edge contact with the elevator floor 16 for pivotal connection thereto. This is accomplished, in this instance, by means of hinges 24 that are secured to the plate 22 proximate to the rearward edge 23 thereof, and countersunk in the floor 16 as at 25 for attachment thereto to provide a pivotal connection between the plate 22 and floor 16 proximate to the threshold or edge of the floor 16 that is adjacent the floor landing 14. The plate 22 is preferably of such length as to extend for substantially the entire width of the elevator floor 16 and is of a width sufficient to overlap the floor edge thereof and bridge the gap 21 for support on the building floor landing 14 so that loaded or unloaded trucks may be displaced thereover for ingress or egress relative to the elevator 15.

So that the elevator floor 16 need not be in perfect alignment with the building floor landing 14 in order to effect traverse of loaded or unloaded trucks thereover, the plate 22 is preferably crowned transversely of the length thereof so as to impart an upward or convex curvature thereto. It is to be noted that the plate 22 overlaps the confronting edges of the floors 14 and 16 only while the elevator is at rest at a floor landing, thereby affording the use of the plate 22 to cover the sill and bridge the gap 21 therebetween. In order to afford the vertical ascent or descent of the elevator 15, the plate mechanism 22 must be withdrawn from contact with the floor landing 14 and preferably displaced in a clockwise direction (viewed from Figure 1) so as to be substan-

tially vertical in its extreme limit of movement, thereby allowing the doors 18 and 19 to close and permit the elevators 15 to move vertically upwardly or downwardly as occasions may require in the required use of the elevator 15.

To this end, the plate 22 may be manually or power actuated to pivot between its extreme limits of movement about the hinges 24 that serve as a pivot or line of fulcrum, 23 about and constituting the rearward edge 23 of the plate 22. As shown, one or more lugs 26 are fixed to the top surface of the plate 22 near an end 27 and proximate to the forward edge 28 thereof so as to provide furcations 29. A link 30 is pivoted between the furcations 29 proximate to the extremity 15 thereof for pivotal attachment by means of a pin 31 that extends therethrough. The link 30 is pivoted at its other extremity to the furcations 32 of a crank arm 33 through the medium of a pin 34. The crank arm 33 terminates in a hub 35 that is mounted on a stub shaft 36 that projects through a wall 37 of the elevator 15 for journaled support in bearing brackets 38 and 39.

It is to be noted that the bearing brackets 38 and 39 are fixed to the floor 16 of the elevator 15 on both sides of the side wall 37 thereof, and the shaft 36 projects therebeyond so as to afford the attachment of a hub 40 that constitutes a part of a link 41. The link 41 in turn is pivotally connected at its other extremity to a furcated bracket 42 through the medium of a pin 43, the furcated bracket 42 constituting a part of a link 44 that protrudes vertically downwardly for connection to a crank arm 45. The crank arm 45 is pivotally connected to the link 44 at its extremities by means of a pin 46 for actuation by an electric motor 47 in that its armature is provided with a hub 48 constituting a part of the crank arm 45 for rotation therewith in conjunction with the motor armature shaft 49.

It is to be noted that the motor 47 is suspended by brackets 50 to the underside 51 of the elevator floor 16, and in this manner the bulk of the mechanism is removed to preclude obstruction in the ingress and egress to and from the elevator 15. Any suitable switch 52 may be utilized for energizing and deenergizing the motor 47 which is in circuit with the power source 53; however, in the present embodiment it is preferred to also employ a limit switch 54 of standard or approved construction which has a lever 55 in the path of trips 56 and 57 that are fixed to the hub 48 constituting a part of the crank arm 45 that rotates with the armature shaft 49.

With this arrangement, the manual switch 52 may be actuated to energize the motor 47 and thereupon the plate 22 will be actuated through the link means 30, 33, 41 and 45 until the trip 56 displaces the limit switch lever 55 so as to break the circuit, thereby bringing the plate 22 to a stop at its extreme limit of movement to bridge the gap 21 and thus enable the traverse of trucks thereover. To elevate the plate 22 to its other extreme limit of movement in a substantially vertical direction, the other button 65 of the switch 52 is depressed so as to again energize the motor for rotation in the opposite direction until the trip 57 moves the limit switch lever 55 in the opposite direction to again break the circuit and thus bring the plate 22 to a position of rest in a vertical upright direction to serve as a stop and safety guard that precludes the accidental removal of trucks from the elevator 15.

It is to be noted, however, that the limit switch 75

54 need not be employed and that a manual switch 52 resorted to for the purpose of both energizing and de-energizing the motor 47 so that the operator or attendant can gauge the entire distance 5 of displacement. This merely requires the resort to a reversible motor 47 that is in circuit with the switch 52 and the source of electrical energy 53 so that the automatic limit switch 54 may be construed as optional equipment depending 10 upon the dictates of commercial practice and the requirements of any particular installation.

It is worthy of note that the electrical circuit includes connections to the elevator control 17 in that the lever 58 thereof has an extension 59 15 that is adapted to contact with a lug or raised projection 60 comprising a part of or pressed into a resilient bar member 61. The resilient member 61 has a terminal 62 fixed to an extremity thereof, and is fixed at its other extremity 63 for 20 yieldable cooperation with a stationary terminal 64 that is in circuit with the manual switch 52 and limit switch 54 so as to make and break the circuit therethrough depending upon the position of the control arm 58 of the elevator 15. When 25 the control arm 15 is in one position or another that is responsible for the ascent or descent of the elevator 15, the resilient bar 61 is urged by its own spring tension to separate the terminal 62 from the terminal 64 in that the lever extension 30 59 is then out of alignment with the lug or projection 60 which allows the spring member 61 to elevate the terminal 62 out of contact with the terminal 64.

Consequently, when the elevator is in operation 35 either in its ascent or descent, it will be impossible to energize the motor 47 that operates the plate 22 when the control arm 58 is in a neutral position that corresponds with bringing the elevator 15 to rest. Then the control arm extension 59 40 is in aligned contact with the lug 60 so as to depress the resilient bar 61 against the urge of its normal springing action to effect contact between the terminals 62 and 64. As a result, the circuit including the motor 47 will be closed or 45 capable of being closed through the manual switch 52 so that the plate 22 may be actuated to one position or another as may be desired. It is to be noted that the control arm extension 59 50 together with the resilient member 61 will be housed or confined in the elevator control mechanism 17 to avoid exposure; however, this illustration on the exterior of the control housing 17 is to clarify the disclosure.

In the modified embodiment disclosed in Figure 55 5, the plate actuating mechanism is entirely concealed below the elevator floor 16 or removed from the interior of the elevator 15 to avoid any obstruction in consequence of its presence as shown in the embodiment described supra. In this instance, the plate 22' has lugs 24' extending from the edge 23' for extension within correspondingly shaped cavities 25' provided in the floor 16' of the elevator 15'. As shown, the lugs 24' have transversely extending bores provided therein to receive the shaft 36' that is journaled in bearings 38' countersunk in the floor 16' of the elevator 15'. As a result, the lugs 24' together with the plate 22' rotate with the shaft 36' that has an extension which projects through the wall 31' of 60 the elevator 15' in much the same way as the projection 40 disclosed in Figure 3.

The link 41' is fixed to the shaft 36' as in the previous embodiment, and is similarly pivoted to the link 44' by means of the pin 43'. A crank 65 arm 45' is pivoted to the other extremity of the

link 44' by means of a pin 46', and connection is effected to the armature shaft 49' of the reversible motor 47' in much the same manner as described supra. The limit switch 54' is supported by means of a bracket to the underside of the elevator floor 16' so that operation is effected and the plate 22' controlled in identically the manner described in detail in connection with the previous embodiments. In this particular instance, however, the link actuating instrumentalities are 10 entirely removed from the interior of the elevator 15, and the operation of the plate 22' is effected without obstructing the loading and unloading of the elevator.

A still simpler embodiment is disclosed in Figure 7 wherein the plate mounting lugs 24'' have an extension 41'' that projects through a notch 25'' provided in the floor 16'' of the elevator 15''. Another link 44'' is connected to the lug extension 41'' through the medium of a pin 43'' that rides in an elongated slot 48'' that is provided in its extremity. The link 44'' is connected to a crank arm 45'' through the medium of the pin 46'', and is actuated or rotated by the reversible motor 47'' in a manner described supra. 20 The limit switch 54'' together with its co-operating mechanism on the crank arm 45'' performs the usual function and is positioned precisely as described in the preceding embodiments.

In Figure 9, still another embodiment of the invention takes the form of a sill plate 22^a that has the lugs 24^a fixed thereto in a manner described in connection with the embodiment disclosed in Figure 7. Instead of the lever extension 41'', however, a gear sector 41^a is fixed 35 to the lugs 24^a so as to mesh with a pinion 45^a fixed to the armature shaft 49^a of the reversible motor 47^a. The limit switch 54^a is positioned on the motor casing 47^a so that its lever 55^a will be actuated in one direction or the other by pins 56^a 40 and 57^a that are the equivalent of the lever arm trips correspondingly numbered and disclosed in Figure 6. The electrical circuit is similar as that shown and described supra, and the mechanism is entirely concealed beneath the elevator floor 45 16^a so as to provide a simple and efficient structure.

In Figure 10 a still further embodiment is disclosed and in this instance the plate 22^b has the lugs 24^b similar to the embodiment disclosed in Figure 7. The lug extensions 41^b are, however, longitudinally slotted as at 42^b to serve as a guide for a pitman block 43^b which is mounted to a crank arm 45^b through the medium of a pivot pin 44^b. The crank arm 45^b is fixed to the 55 crank shaft 49^b in the manner described supra. The crank arm 45^b has an extension 55^b provided with a pin that is adapted to move in the path of the trips 56^b and 57^b of a limit switch 54^b. In consequence thereof, the plate mechanism 22^b 60 will be actuated between its extreme limits of movement and controlled in a manner described supra. The crank arm 45^b is rotated by the uni-directional motor 47^b.

In Figure 11 the structure is similar to that shown in Figure 7 with the addition of a counterweight 66^c that is slidably mounted on a lever 67^c. A set screw 68^c projects through the wall of the counterweight 66^c to contact the lever arm 67^c so as to afford adjustment and vary the effect 65 of the weight 66^c upon the plate 22^c. As shown, the lever 67^c terminates in a hub 69^c that affords attachment to the shaft 36^c to which the lugs 24^c 70 are attached for mounting the plate 22^c. In consequence thereof, the required power of the 75

reversible motor 47^c is minimized so as to more economically effect the operation of the plate 22^c and to provide for a smaller and less expensive motor to serve that purpose.

5 In Figure 12 the counterweight 66^c is substituted by a spring 66^d that has one extremity thereof mounted to the floor supporting angle iron 70^d with the other extremity fixed to a pin 71^d carried by the lever 44^d that is connected to 10 actuate the plate 22^d in the manner and according to the details of construction shown in Figure 7, counterbalance the weight of the plate 22^d and enables the use of a smaller motor that is less expensive and is productive of cheaper maintenance. It is worthy of note that the motor 47^d may be entirely dispensed with, and that a hand lever 72 is substituted in lieu thereof for 15 connection to the plate 22^d through instrumentalities such as described in any one of the previous embodiments.

With the arrangement of parts above described, it will be apparent that a single sill plate 22 is required for each elevator rather than for every floor landing as heretofore provided, and that 25 such can be utilized with great speed and advantage to bridge the gap 21 between the floors of a building and elevator structure as well as to serve as a safety expedient in its vertically erect position to preclude the accidental removal of 30 trucks or other cargo that is being carried by the elevator to its desired destination on any of the desired floors 14 of the building structure.

Various changes may be made in the embodiment of the invention herein specifically described without departing from or sacrificing any of the advantages of the invention as defined in the appended claims.

I claim:

1. In an elevator structure having a floor for 40 selective horizontal alignment with superposed floors of a building structure, of a metallic plate pivotally associated with said elevator floor so as to be displaceable in overlapping relation with an edge of said elevator floor which is adjacent 45 a building floor, link means for displacing said metallic plate to an operative or inoperative position respecting said building floors to enable or preclude the movement of trucks from one structure to the other structure, means for counterbalancing said plate so as to minimize the required power for effecting plate displacement, and lever crank means operatively connected to 50 said link means, said lever crank means and link means being so connected as to retain said plate 55 in its extreme positions of movement.

2. In an elevator structure having a floor for 60 selective horizontal alignment with superposed floors of a building structure, of a metallic plate pivotally associated with said elevator floor so as to be displaceable in overlapping relation with an edge of said elevator floor which is adjacent a building floor, link means for displacing said metallic plate to an operative or inoperative position respecting said building floors to enable or 65 preclude the movement of trucks from one structure to the other structure, means for counterbalancing said plate so as to minimize the required power for effecting plate displacement, a motor operatively connected to said link means 70 for imparting movement to said plate, and limit switches on said motor for automatically governing the operation of said plate within predetermined limits.

3. In an elevator structure having a floor for 75 selective horizontal alignment with superposed

floors of a building structure, of an elongated metallic plate extending along an edge of said elevator floor, there being a notch of corresponding plate length in said elevator floor to receive an elongated edge of said plate, pivotal means 5 mounted on the underside of said elevator floor adjacent said notch for attachment to said last named plate edge mounted to lie flush with said elevator floor, means for displacing said metallic plate about said pivotal means in overlapping relation with the threshold of said elevator floor to rest on a building floor in substantially horizontal alignment therewith to bridge the gap between said elevator and building floor structures, and means interposed between said displacing means and said metallic plate to retain the latter in its extreme positions of displacement.

4. In an elevator structure having a floor for 20 selective horizontal alignment with superposed floors of a building structure, of an elongated metallic plate extending along an edge of said elevator floor, there being a notch of corresponding plate length in said elevator floor to receive an elongated edge of said plate, pivotal means 25 mounted on the underside of said elevator floor adjacent said notch for attachment to said last named plate edge mounted to lie flush with said elevator floor, a motor fixed to the underside of said elevator floor proximate to said pivotal 30 means, and interengaging means interposed between said pivotal means and motor for displacing said metallic plate about said pivotal means in overlapping relation with the threshold of said elevator floor to rest on a building floor 35 in substantially horizontal alignment therewith, thereby bridging the gap between said elevator and building floor structures.

5. In an elevator structure having a floor for 40 selective horizontal alignment with superposed floors of a building structure, of an elongated metallic plate extending along an edge of said elevator floor, there being a notch of corresponding plate length in said elevator floor to receive an elongated edge of said plate, pivotal means 45 mounted on the underside of said elevator floor adjacent said notch for attachment to said last named plate edge mounted to lie flush with said elevator floor, a motor fixed to the underside of said elevator floor proximate to said pivotal 50 means, and link means interposed between said pivotal means and motor for displacing said metallic plate about said pivotal means in overlapping relation with the threshold of said elevator floor to rest on a building floor in substantially 55 horizontal alignment therewith, thereby bridging the gap between said elevator and building floor structures.

6. In an elevator structure having a floor for 60 selective horizontal alignment with superposed floors of a building structure, of an elongated metallic plate extending along an edge of said elevator floor, there being a notch of corresponding plate length in said elevator floor to receive an elongated edge of said plate, pivotal means 65 mounted on the underside of said elevator floor adjacent said notch for attachment to said last named plate edge mounted to lie flush with said elevator floor, a motor fixed to the underside of said elevator floor proximate to said pivotal 70 means, and interengaging gear means interposed between said pivotal means and motor for displacing said metallic plate about said pivotal means in overlapping relation with the threshold of said elevator floor to rest on a building floor 75

in substantially horizontal alignment therewith, thereby bridging the gap between said elevator and building floor structures.

7. In an elevator structure having a floor for selective horizontal alignment with superposed floors of a building structure, of an elongated metallic plate extending along an edge of said elevator floor, there being a notch of corresponding plate length in said elevator floor to receive an elongated edge of said plate, pivotal means mounted on the underside of said elevator floor adjacent said notch for attachment to said last named plate edge mounted to lie flush with said elevator floor, a motor fixed to the underside of said elevator floor proximate to said pivotal means, link means interposed between said pivotal means and motor for displacing said metallic plate about said pivotal means in overlapping relation with the threshold of said elevator floor to rest on a building floor in substantially horizontal alignment therewith, thereby bridging the gap between said elevator and building floor structures, and means for counter-balancing the gravity urge on said plate to minimize the required power for rendering operative said motor.
8. In an elevator structure having a floor for

selective horizontal alignment with superposed floors of a building structure, of an elongated metallic plate extending along an edge of said elevator floor, there being a notch of corresponding plate length in said elevator floor to receive an elongated edge of said plate, pivotal means mounted on the underside of said elevator floor adjacent said notch for attachment to said last named plate edge mounted to lie flush with said elevator floor, a motor fixed to the underside of said elevator floor proximate to said pivotal means, link means interposed between said pivotal means and motor for displacing said metallic plate about said pivotal means in overlapping relation with the threshold of said elevator floor to rest on a building floor in substantially horizontal alignment therewith, thereby bridging the gap between said elevator and building floor structures, means for counter-balancing the gravity urge on said plate to minimize the required power for rendering operative said motor, and limit switches operatively connected to said motor to automatically govern the predetermined limit of plate displacement.

ELISHA E. ALEXANDER. 25
